Des. 179,569
Patented Jan. 22, 1957

179,569

ELECTRIC MEGAPHONE

Frederick Lee Hardesty, Silver Spring, Md.

Application September 2, 1955, Serial No. 37,762

Term of patent 14 years

(Cl. D26—14)

Fig. 1 is a perspective view of an electric megaphone embodying my new design;

Fig. 2 is a side elevational view thereof;

Fig. 3 is a rear view thereof; and

Fig. 4 is a front view thereof.

I claim:

The ornamental design for an electric megaphone, substantially as shown.
